BREECHBLOCK

James L. Riedl, Laguna Niguel, Calif.
(15124 Weststate, Westminster, Calif. 92683)

Filed Nov. 6, 1972, Ser. No. 303,727

Term of patent 14 years

Int. Cl. D22—99

U.S. Cl. D22—7

FIG.1

FIG.2

FIG.3

FIG.4

FIG.5

FIG.6

FIG.7

FIG.8

FIG. 1 is a perspective view of the breechblock in which its forward face, right side and lower face are visible;

FIG. 2 is a perspective view of the breechblock showing its right side, upper face, and rearward side; and

FIGS. 3, 4, 5, 6, 7 and 8 are views in elevation of the right side, forward face, left side, rear side, upper face, and lower face, respectively, of the breechblock.

I claim:

The ornamental design for a breechblock, substantially as shown and described.
